US0D1065523S

(12) **United States Design Patent** (10) **Patent No.:** **US D1,065,523 S**
(45) **Date of Patent:** **** Mar. 4, 2025**

(54) **VALVE**

(71) Applicant: **Medline Industries, LP**, Northfield, IL (US)

(72) Inventors: **Lisa Bauer**, Buffalo Grove, IL (US); **Luke Stevens**, Wildwood, IL (US); **Michael Turturro**, Arlington Heights, IL (US); **Paulina Lowkis**, Barrington, IL (US); **Morgan Uridil**, Evanston, IL (US); **Douglas Komandt**, Chicago, IL (US)

(73) Assignee: **Medline Industries, LP**, Northfield, IL (US)

(**) Term: **15 Years**

(21) Appl. No.: **29/904,380**

(22) Filed: **Oct. 5, 2023**

Related U.S. Application Data

(60) Continuation of application No. 29/858,634, filed on Nov. 2, 2022, now Pat. No. Des. 1,010,113, which is (Continued)

(57) **CLAIM**

The ornamental design for a valve, as shown and described.

DESCRIPTION

FIG. 1 is a front, top perspective view of a valve of our new design;

FIG. 2 is a rear, bottom perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the valve that form no part of the claimed design.

1 Claim, 7 Drawing Sheets

Related U.S. Application Data

a division of application No. 29/777,593, filed on Apr. 7, 2021, now Pat. No. Des. 972,721, which is a division of application No. 29/696,798, filed on Jul. 1, 2019, now Pat. No. Des. 920,504.
